UNITED STATES PATENT OFFICE.

ISAAC FRANCIS FARLOW, OF ROCKAWAY, NEW JERSEY.

GARMENT-SLEEVE.

1,147,155.

Specification of Letters Patent. Patented July 20, 1915.

Application filed October 2, 1913. Serial No. 792,992.

To all whom it may concern:

Be it known that I, ISAAC FRANCIS FARLOW, a citizen of the United States, and a resident of Rockaway, in the county of Morris and State of New Jersey, have invented 5 certain new and useful Improvements in Garment-Sleeves, of which the following is a specification.

This invention relates to an improvement 10 in garment sleeves, more particularly short or shirt waist sleeves.

It is often desirable, especially in the summer, to roll up the sleeves above the elbow to secure greater comfort and relief from 15 the heat. The sleeves are also rolled up at times to prevent the cuff from becoming soiled when a person is at work. At the present time, when the sleeves are so rolled 20 up, they present a very untidy appearance, not only due to the thickness of the rolled up portion, but also to the fact that the wrong side of the material is exposed.

In order to remedy this condition and to 25 enable the wearer to secure a greater degree of comfort, I provide a short length sleeve having a lining of the same material as the sleeve itself and exposing the right side thereof, thus forming a sleeve of double material. By rolling up a portion of the sleeve 30 so formed, it will simulate an ordinary sleeve rolled up above the elbow, but have the advantage of exposing only the right side of the material, and the rolled up portion will not have so many folds as to render it thick and cumbersome looking, but 35 will present a flat and even appearance around the arm. I further provide the short length sleeve with means whereby an extension sleeve portion, having the usual cuff, 40 may be secured to form a full length sleeve. Thus, the extension portion may be easily detached whenever desired and conveniently placed in the pocket, both saving the cuffs from becoming quickly soiled and leading a 45 rolled up short length sleeve presenting a very neat appearance and affording a greater degree of coolness and comfort to the wearer.

Further objects and advantages will more 50 fully appear in the following detailed description and the features of novelty will be particularly pointed out in the claims.

In the drawings, Figure 1 is a longitudinal view of my improved short length sleeve before it is doubled back inwardly upon 55 itself to constitute a lining. Fig. 2 is a view

of the sleeve shown in Fig. 1, doubled inwardly upon itself and the edge stitched to the shoulder portion of the shirt. Fig. 3 is a view of the sleeve with a portion at the bottom thereof folded outwardly back upon 60 itself to form a cuff. Fig. 4 is a view of the sleeve shown in Fig. 3, with a plurality of buttons sewed upon the cuff. Fig. 5 is a view of the sleeve provided with buttonholes adjacent the upper edge of the cuff. Fig. 6 is a detail view of a band with buttons sewed 65 thereon for engaging the buttonholes in the cuff shown in Fig. 5. Fig. 7 is a view of my improved extension sleeve portion provided with buttonholes near the upper end and a 70 hem having a slit at the upper end thereof. Fig. 8 is a detail view of an elastic band which may be inserted in the extension sleeve portion shown in Fig. 7. Fig. 9 is a view 75 of the short length sleeve with the extension buttoned thereto to form a full length sleeve. Fig. 10 is a modification in which the extension is inserted within the short length sleeve.

Referring in detail to the drawings, my 80 improved sleeve consists of a unitary length, the lower portion 10 of which being turned up into and within the upper portion 11. The end of the portion 10 may be then sewed 85 to the shoulder of the shirt at 12 or at any point adjacent thereto, thus forming the short length double sleeve. It will thus be seen that the right side of the material will be exposed both on the inside of the sleeve as 90 well as the outside. By rolling up a portion of the sleeve to form a cuff 13, the sleeve will present a very neat appearance, due to the fact that the wrong side of the material is nowhere exposed and will simulate an ordinary sleeve rolled up above the elbow, with 95 the exception that it will present a much neater appearance. Upon the cuff portion 13, I may conveniently apply buttons 14, (Fig. 4) to which may be secured an extension sleeve portion 15, (Fig. 7) having the ordinary cuff 16 attached thereto and provided with buttonholes 17 near the upper end thereof, thus forming a full length sleeve, as shown in Fig. 9.

In Figs. 5 and 6, I have shown a modification in the application of the buttons 14 whereby the same may be sewed onto the band 13. In this form, I provide the cuff portion 13 with buttonholes 19. Upon the band 13, I sew a corresponding number of 100 110

buttons and encircle the sleeve therewith beneath the cuff, allowing the buttons to protrude through the buttonholes. After the insertion of the buttons in the buttonholes, 5 this form presents practically the same appearance as that shown in Fig. 4. However, in this form, the buttons may be readily removed from the sleeve when the garment is being washed.

10 In Fig. 9, I have illustrated the extension portion 15 buttoned onto the short length sleeve, thus constituting a full length sleeve. It may be desirable to provide other means for securing the extension portion upon the 15 arm than by the use of buttons. To this end, I provide the upper edge of the extension portion 15 with a hem 20, leaving a slit 21 for the insertion of an elastic band 22, (Fig. 8). The extension portion may thus 20 be inserted beneath the short length sleeve and due to the elastic band, the former will be held firmly upon the arm of the wearer above the elbow as shown in Fig. 10. Obviously, the extension portion may be made 25 wide enough adjacent its upper end to be worn over the cuff of the short length portion and the elastic band will hold the former securely upon the latter if desired.

It will be readily understood that the 30 portions 10 and 11 may, without departing from my invention, be separate pieces of the same material sewed together in substantially the manner contemplated and described, or the portion 10 may be of silk, 35 satin or other fine material, so that when the cuff is formed upon the short length sleeve, the same will have a facing of the material of the lining and thus render the shirtwaist more attractive. This form is especially 40 adapted for women's wear.

It will thus be seen that I have provided 45 a sleeve which may be full length or short length as desired. When worn in summer, the sleeve may be converted into a short length sleeve by simply removing the extension portion. The short length sleeve thus remaining, will, due to the fold or cuff thereon, simulate the ordinary rolled up sleeve with the exception that it will present 50 a much neater appearance due to the thinness of the folded portion and the fact that the right side of the material is exposed instead of the wrong side as in the ordinary sleeve. Moreover, the extension portion 55 may be readily put on and removed, thus affording all of the advantages of the full length sleeve in addition to the advantages above pointed out.

Having thus described my invention, I

claim as new and desire to secure by Letters 60 Patent:

1. A short length sleeve comprising a 65 length of material doubled back upon itself, the lower portion of said length being folded inwardly of the upper portion for a considerable portion of its length and permanently secured thereto to form a short sleeve of double material, the right side of the material being exposed both on the inside and outside of the sleeve, said sleeve always presenting the right side of material to view when rolled up to any degree, and an upturned fold at the bottom of the sleeve forming a cuff, the right side of the material only being exposed, an extension portion having a cuff at the lower end thereof, and means for securing said extension to the first mentioned sleeve portion. 70

2. A sleeve comprising a main short member of double material, an upturned portion 80 adjacent the end thereof to form a cuff, the right side of the material being exposed both on the inside and outside of said portion, said cuff having a plurality of buttonholes, a band, a plurality of buttons secured thereto, said band surrounding the sleeve portion beneath the cuff and the buttons extending through the buttonholes, and an extension sleeve portion provided with 85 buttonholes adjacent its upper end through 90 which the buttons are adapted to be inserted to constitute a full length sleeve.

3. A sleeve comprising a short main member of double material, a folded portion at the bottom of said member forming a cuff, 95 the right side of the material only being exposed, an extension portion, means for detachably securing said extension portion upon the first mentioned portion, and means for shirring the upper ends of the extension 100 portion to tighten the same about the arm.

4. A sleeve comprising a short main member of double material, a folded portion at the bottom of said portion forming a cuff, 105 the right side of the material only being exposed, an extension portion, means for detachably securing said extension portion upon the first mentioned portion, and means for shirring the upper ends of the extension 110 portion to tighten the same about the arm comprising a hem at the upper end of the extension, and an elastic band removably held therein.

ISAAC FRANCIS FARLOW.
